12 Claims. (Cl. 260—526)

This invention is directed to a process for the production of olefinically-unsaturated organic acids. More particularly, this invention is directed to the pyrolysis of epsilon-caprolactones to produce the olefinically-unsaturated acids and has for an object the provision of a process for manufacturing olefinically-unsaturated acids of a predetermined type. More specifically, it is an object of this invention to provide a process for the production of delta-olefinically-unsaturated organic acids from the corresponding epsilon-caprolactones, and in the case of epsilon-alkyl-epsilon-caprolactones, epsilon-olefinically-unsaturated organic acids. A particular object of the invention is to provide a process for the production of delta-hexenoic acid to the substantial exclusion of gamma-hexenoic acid which comprises pyrolyzing epsilon-caprolactone.

Heretofore, according to customary practices, the methods of producing olefinically-unsaturated acids from lactones involve the hydrolysis of the lactone to the corresponding hydroxy acids followed by dehydration to provide the corresponding unsaturated acids usually as a mixture of isomers. Random distribution of isomers occurs and it is impossible, from a practical standpoint, to isolate the respective isomers.

By virtue of the process of this invention, random distribution of isomers is substantially avoided and olefinically-unsaturated acids of a desired type can now be produced with greater selectivity and ease.

Quite unexpectedly it has been discovered that epsilon-caprolactones can be cracked under pyrolysis conditions whereas the corresponding delta- and gamma-lactones can not. This is indeed surprising in view of the fact that 5-membered rings have substantially the same degree of strain as the 7-membered rings, yet when the gamma-lactones are subjected to pyrolysis conditions they do not crack. Normally, it would be expected that the epsilon-caprolactones would be similar in reactivity to the gamma- and delta-lactones.

It has been discovered that epsilon-caprolactones can be pyrolyzed to specific unsaturated acids to the substantial exclusion of undesirable mixtures of isomer which are normally to be expected under conditions involving hydrolysis and dehydration of the epsilon-caprolactone as discussed, supra. As used herein the term "substantial exclusion" is intended to mean the production of a reaction mixture containing the desired isomer in predominating amounts and the undesired isomer in amounts of the order of less than ten percent by weight of the total contained unsaturated acids.

The process of this invention is directed to the preparation of olefinically-unsaturated acids from epsilon-caprolactones corresponding to the general formula:

wherein, R, R¹, R², and Y represent hydrogen atoms and lower alkyl groups containing from 1 through 8 carbon atoms, except that when R¹ and R² are both hydrogen, Y is hydrogen; which comprises pyrolyzing an epsilon-caprolactone in the vapor phase and recovering the corresponding unsaturated acid. A preferred group of epsilon-lactones suitable for employment in the process of this invention include epsilon-caprolactones wherein the total number of carbon atoms in the alkyl groups

10 does not exceed twelve.

Among the epsilon-caprolactones which have been found suitable for employment in the process of this invention are:

- 15 Epsilon-caprolactone
- Gamma-isopropyl-epsilon-caprolactone
- Alpha-methyl-epsilon-caprolactone
- Beta-methyl-epsilon-caprolactone
- Gamma-methyl-epsilon-caprolactone
- Delta-methyl-epsilon-caprolactone
- 20 Epsilon-methyl-epsilon-caprolactone
- Alpha-ethyl-epsilon-caprolactone
- Beta-ethyl-epsilon-caprolactone
- Gamma-ethyl-epsilon-caprolactone
- Delta-ethyl-epsilon-caprolactone
- Epsilon-ethyl-epsilon-caprolactone
- Alpha,beta-dimethyl-epsilon-caprolactone
- Alpha,gamma-dimethyl-epsilon-caprolactone
- Alpha,delta-dimethyl-epsilon-caprolactone
- 30 Alpha,epsilon-dimethyl-epsilon-caprolactone
- Beta,gamma-dimethyl-epsilon-caprolactone
- Beta,delta-dimethyl-epsilon-caprolactone
- Beta,epsilon-dimethyl-epsilon-caprolactone
- Gamma,delta-dimethyl-epsilon-caprolactone
- 35 Gamma,epsilon-dimethyl-epsilon-caprolactone
- Delta-epsilon-dimethyl-epsilon-caprolactone
- Beta,beta,delta-trimethyl-epsilon-caprolactone
- Alpha,beta,gamma-trimethyl-epsilon-caprolactone
- Alpha,beta,delta-trimethyl-epsilon-caprolactone
- 40 Alpha,beta,epsilon-trimethyl-epsilon-caprolactone
- Beta,gamma,delta-trimethyl-epsilon-caprolactone
- Beta,gamma,epsilon-trimethyl-epsilon-caprolactone
- Gamma,delta,epsilon-trimethyl-epsilon-caprolactone
- Alpha,ethyl-beta-methyl-epsilon-caprolactone
- Alpha-ethyl-gamma-methyl-epsilon-caprolactone
- 45 Alpha-ethyl-delta-methyl-epsilon-caprolactone
- Alpha-ethyl-epsilon-methyl-epsilon-caprolactone
- Beta-ethyl-alpha-methyl-epsilon-caprolactone
- Beta-ethyl-gamma-methyl-epsilon-caprolactone
- Beta-ethyl-delta-methyl-epsilon-caprolactone
- 50 Beta-ethyl-epsilon-methyl-epsilon-caprolactone
- Gamma-ethyl-alpha-methyl-epsilon-caprolactone
- Gamma-ethyl-beta-methyl-epsilon-caprolactone
- Gamma-ethyl-delta-methyl-epsilon-caprolactone
- 55 Gamma-ethyl-epsilon-methyl-epsilon-caprolactone
- Delta-ethyl-alpha-methyl-epsilon-caprolactone
- Delta-ethyl-beta-methyl-epsilon-caprolactone
- Delta-ethyl-gamma-methyl-epsilon-caprolactone
- Delta-ethyl-epsilon-methyl-epsilon-caprolactone
- 60 Epsilon-ethyl-alpha-methyl-epsilon-caprolactone
- Epsilon-ethyl-beta-methyl-epsilon-caprolactone
- Epsilon-ethyl-gamma-methyl-epsilon-caprolactone
- Epsilon-ethyl-delta-methyl-epsilon-caprolactone
- Alpha,alpha-dimethyl-epsilon-caprolactone
- Beta-beta-dimethyl-epsilon-caprolactone
- 65 Gamma,gamma-dimethyl-epsilon-caprolactone
- Alpha,alpha,delta-trimethyl-epsilon-caprolactone
- Beta,beta,gamma-trimethyl-epsilon-caprolactone
- Gamma,gamma,epsilon-trimethyl-epsilon-caprolactone
- Beta,beta-dimethyl-gamma-ethyl-epsilon-caprolactone

70 As used herein the term "pyrolyzing" is intended to mean cracking of the epsilon-caprolactones or heating to

a temperature sufficiently high to crack the epsilon-caprolactones and includes conditions of temperature of from, at, or above the boiling point of the selected caprolactone starting material, to about 800° C. More particularly, the pyrolysis conditions of this invention involve temperatures of the order of from about 400° C. to about 600° C. at normal atmospheric pressures.

It has been determined that the residence time for optimum conversion in the reaction zone of the heated selected epsilon-caprolactone is a function of the temperature of the reaction. It has been found that at the temperatures above specified, the reaction can be accomplished at a rate of from about 20 ml. per hour to about 1000 ml. per hour in a heated zone one inch in diameter and three feet long, at practical efficiencies of epsilon-caprolactones to unsaturated acids. Expressed in terms of space velocity (liters/liter/hour) practical yields and conversions of epsilon-caprolactones are obtained at space velocities of from 20 to 3000 approximately.

In carrying out the process of this invention an epsilon-caprolactone, such as epsilon-caprolactone, is fed at a rate of from about 200 ml. per hour through a pyrolysis tube such as a stainless steel tube (1 inch by 36 inches) preferably packed with "Filtros" or glass beads to give an approximate free space of 70 percent at a temperature of 560° C. The effluent from the pyrolysis tube is analyzed for acid content.

The pyrolysis mixture may be analyzed for acid by titration with base. Water and ice are usually added to the sample for analysis and the cold mixture is titrated quickly with 0.5 N sodium hydroxide or potassium hydroxide. Under these conditions the lactone ring is not opened by the base.

Isolation of the unsaturated acids is simplified when a high conversion per pass is obtained since the starting lactone and the unsaturated acid usually boil fairly near each other. However, pyrolysis efficiencies are usually better, especially in the case of epsilon-caprolactone, if the conditions chosen are mild enough to avoid large amounts of gas formation during the pyrolysis. The products may be isolated by the usual methods such as fractional distillation or extraction of the acid by means of sodium bicarbonate or sodium carbonate at low temperatures from a solution of the reaction mixture in chloroform or some other water-insoluble solvent. The 45 unused epsilon-caprolactone may then be recycled back to the pyrolysis tube.

Example I

Epsilon-caprolactone (100 ml.) was fed at the rate of 200 ml./hr. through a stainless steel tube (1 inch by 36 inches) packed with "Filtros" which was heated to 440-450° C. This corresponded to a space velocity of approximately 343. The effluent from the tube was condensed and titrated for acid. The effluent was found to contain 5 percent 5-hexenoic acid.

Example II

Epsilon-caprolactone was fed through the tube described in Example I at a rate of 280 ml./hr. at a temperature of 550° C. (space velocity equals 560). The tube effluent which condensed was titrated with base and was found to contain 19 percent 5-hexenoic acid.

Example III

Epsilon-methyl-epsilon-caprolactone was fed through the tube described in Example I at a rate of 320 ml./hr. at a temperature of 470° C. (space velocity equals 495). A titration of the condensed tube effluent indicated a 67 percent conversion to acid. Fractional distillation of the condensate gave a product boiling at 97° C. at 5 mm. pressure and having a refractive index of 1.4390 (n_D^{20}). Titration with base indicated a purity of 96 percent calculated as 6-heptenoic acid. An examination of the infrared spectrum of this product indicated that the double bond was in the terminal position. Very little (estimated 65

5 percent) absorption characteristic of trans internal double bonds was observed.

Example IV

5 The tube used in Examples I, II and III was coated on the inside with "Isolute" cement and after drying was packed with 5 mm. glass beads. Through this tube was passed 500 grams of epsilon-caprolactone at a rate of 160 ml./hr. at an average temperature of 560° C. The space velocity was approximately 335. There was obtained 475 grams of tube condensate. Analysis indicated that the reaction mixture contained 17.4 percent of 5-hexenoic acid.

Example V

A sample of epsilon-caprolactone (200 grams) was passed through the tube used in Example IV at a temperature of 625° C. and a rate of 100 ml./hr. (space velocity equals 223). The tube effluent (127 grams) containing 32.6 percent 5-hexenoic acid as indicated by analysis.

Example VI

25 A sample of epsilon-caprolactone (300 grams) was fed through the tube used in Examples IV and V at a rate of 50 ml./hr. at a temperature of 575° C. (space velocity equals 104). The tube effluent (235 grams) contained 26.7 percent 5-hexenoic acid as indicated by analysis. The tube products from Examples IV, V and VI were composited and distilled under reduced pressure. There 30 was isolated 5-hexenoic acid, boiling at 84° C. at 4 mm. and having a refractive index of 1.4331.

Example VII

35 A sample of epsilon-methyl-epsilon-caprolactone (585 grams) was fed through the tube used in Examples IV, V and VI at 135 ml./hr. at a temperature of 535° C. (space velocity equals 277). The tube effluent (553 grams) contained 82.2 percent 6-heptenoic acid as indicated by analysis. Distillation of the reaction mixture gave the same product as obtained in Example III.

What is claimed is:

1. A process for the production of olefinically-unsaturated organic acids which comprises passing an epsilon-caprolactone corresponding to the general formula:

50 wherein, R, R¹, R², and Y represent hydrogen atoms and lower alkyl groups containing from 1 through 8 carbon atoms, except that when R¹ and R² are both hydrogen, Y is hydrogen, at a space velocity in the range of from about 20 liters/liter/hour to about 3000 liters/liter/hour through a heated reaction zone maintained at a temperature in the range of at or above the boiling point of said lactone to about 800° C.

55 2. A process for the production of olefinically-unsaturated organic acids which comprises passing an epsilon-caprolactone corresponding to the general formula:

60 wherein, R, R¹, R², and Y represent hydrogen atoms and lower alkyl groups containing from 1 through 8 carbon atoms, except that when R¹ and R² are both hydrogen, Y is hydrogen, at a space velocity in the range of from about 20 liters/liter/hour to about 3000 liters/liter/hour through a heated reaction zone maintained at a temperature in the range of from about 400° C. to about 600° C.

65 3. A process for the production of delta-hexenoic acid to the substantial exclusion of gamma-hexenoic acid which

comprises passing epsilon-caprolactone at a space velocity in the range of from about 20 liters/liter/hour to about 3000 liters/liter/hour through a heated reaction zone maintained at a temperature in the range of from about 400° C. to about 600° C.

4. A process for the production of epsilon-unsaturated acids to the substantial exclusion of delta-unsaturated acids which comprises passing an epsilon-lower-alkyl-epsilon-caprolactone at a space velocity in the range of from about 20 liters/liter/hour to about 3000 liters/liter/hour through a heated reaction zone maintained at a temperature in the range of from about 400° C. to about 600° C.

5. A process for the production of epsilon-unsaturated acids to the substantial exclusion of delta-unsaturated acids which comprises passing epsilon-methyl-epsilon-caprolactone at a space velocity in the range of from about 20 liters/liter/hour to about 3000 liters/liter/hour through a heated reaction zone maintained at a temperature in the range of from about 400° C. to about 600° C.

6. A process for the production of olefinically-unsaturated acids which comprises pyrolyzing an epsilon-methyl-epsilon-caprolactone.

7. A process for the production of an olefinically unsaturated organic acid which comprises pyrolyzing an alkyl-epsilon-caprolactone.

8. A process for the production of olefinically-unsaturated organic acids which comprises heating an epsilon-caprolactone corresponding to the general formula:

wherein, R, R¹, R², and Y represent hydrogen atoms and lower alkyl groups containing from 1 through 8 carbon atoms, except that when R¹ and R² are both hydrogen, Y is hydrogen, at a temperature in the range of at or above the boiling point of said lactone to about 800° C.

9. A process for the production of olefinically-unsaturated organic acids which comprises pyrolyzing an epsilon-caprolactone corresponding to the general formula:

wherein, R, R¹, R², and Y represent hydrogen atoms and lower alkyl groups containing from 1 through 8 carbon atoms, except that when R¹ and R² are both hydrogen, Y is hydrogen.

5 10. A process for the production of olefinically-unsaturated organic acids which comprises pyrolyzing epsilon-caprolactone.

11. A process for pyrolyzing epsilon-caprolactones to produce an olefinically-unsaturated organic acid which 10 comprises heating an epsilon-caprolactone corresponding to the general formula:

15 wherein, R, R¹, R², and Y represent hydrogen atoms and lower alkyl groups containing from 1 through 8 carbon atoms, except that when R¹ and R² are both hydrogen, Y is hydrogen.

20 20. A process for pyrolyzing epsilon-caprolactone to produce an olefinically-unsaturated organic acid which comprises heating an epsilon-caprolactone corresponding to the general formula:

25 30 wherein, R, R¹, R², and Y represent hydrogen atoms and lower alkyl groups containing from 1 through 8 carbon atoms, except that when R¹ and R² are both hydrogen, Y is hydrogen.

35 35. A process for pyrolyzing epsilon-caprolactone to produce an olefinically-unsaturated organic acid which comprises heating an epsilon-caprolactone corresponding to the general formula:
